MACHINE FOR IMPACTING PIGMENTS
AGAINST A ROTATING DISK ELEMENTHarold R. Rafton, Andover, Mass., assignor to
Rafton Engineering Corporation, a corporation
of Massachusetts

Application March 16, 1943, Serial No. 479,373

3 Claims. (Cl. 241—186)

1

My invention relates to machines for treating materials by striking. It more particularly relates to a machine for the treatment by striking of solids in liquid suspension, and more particularly pigments in liquid suspension. It further relates to the use in a machine of a rotating element or rotor element provided with one or more striking surfaces, preferably a plurality of striking surfaces.

My invention further relates to a machine which provides for the striking of material, for example a liquid, or liquid suspension, in the form of at least one stream, jet or the like discharged under pressure, particularly in a plane of rotation of the rotor element, directed substantially toward the center of rotation of said element.

The principal object of my invention is the provision of a machine suitable for the treatment of materials, and particularly for the treatment of solids in liquid suspension, to change the characteristics of the materials, and particularly to impart specific and controlled characteristics to the materials.

A further object is to provide an apparatus for the treatment of materials of the character referred to, wherein jets of the material are subjected to a highly efficient impacting or shocking action to secure the desired results.

A further object is to provide such an apparatus wherein a highly effective treatment of the material by impact or shock is accomplished with minimum power by eliminating movement of the shock elements in any substantial contact with the material except that being fed thereto in the jets from suitable nozzles.

A further object is to provide a novel apparatus of the character referred to wherein a rotary element is employed having striking faces so disposed with respect to the jets of material projected thereto as to effect the most efficient possible shocking action on the material.

A further object is to provide an apparatus of the character referred to wherein the parts are so constructed as to provide for the substantially immediate escape of the material from contact with the rotating member after the shock action has been performed, whereby the rotary member is prevented from rotating in any appreciable body of the material to minimize the amount of power required for operating the apparatus.

Other objects and advantages of my invention will become apparent during the course of the following description.

This application is a continuation in part of

2

my copending application Serial No. 449,492, filed July 2, 1942. Such application was abandoned in favor of my copending application Serial No. 718,649, filed December 27, 1946, in which is disclosed the treatment of material, particularly calcium carbonate suspended in a liquid, by a rotating element provided with striking surfaces, and in which the preferred machine for conducting this treatment is described, but not claimed.

10 (My said application Serial No. 718,649 is a continuation of and contains all of the disclosure in my said abandoned application Serial No. 449,492.) This machine, described in further detail, and illustrated by drawings, is claimed

15 herein. (This application is also a continuation in part of two other of my copending applications which will be specifically referred to later herein.)

Machines which have hitherto been proposed for striking materials, for example liquids, or 20 solids in suspension in liquids, have usually operated either with the rotating element dipping into or immersed in the liquid, or with the liquid introduced at or near the center of the surface of the rotating element and discharged at its 25 periphery, or with the liquid introduced near the periphery of the rotating element, or the like, in many cases in conjunction with a fixed or moving primary or secondary impact member, surface or surfaces. In any case where the rotating element is disposed in, or is exposed to, a substantial volume of the liquid, the power requirements are excessive and furthermore all the liquid may not be treated, except after a prolonged time, and where solids are treated in liquid suspension the 30 wear on the moving element is great. In the types of machines where the liquid is introduced at or near the center or somewhere near the periphery, the power requirement, although somewhat less, is still large, and when using solids 35 in liquid suspension, the wear, which is very substantial, is not compensated for and the rotating elements have to be quickly replaced. Defects 40 such as these have made such machines uneconomical, difficult to maintain, and even, in many instances, entirely impractical for commercial operation.

My machine has the advantages, among others, that it is economical of power because the material to be treated, for example a liquid, occupies 50 only a small space at the points of contact with the striking surfaces of the rotor element, the power being employed directly in striking the liquid and not in pumping, circulating, swirling, or projecting it, that all the liquid is struck at every contact with the striking surfaces, that all

the wear on the striking surfaces, if there is wear, is that resulting from useful work, that extremely simple means are provided for compensating for or avoiding this wear, and that more intense effects and more efficient results are obtained. This combination of relatively low power, more intense effects, and high efficiency makes my machine unique and, in all its adaptations, the problem of wear is provided for in a simple and effective manner, whereby the machine may be run efficiently and economically, in substantially continuous operation if desired.

The invention will be better understood from the accompanying drawings and the detailed description based thereon. In the drawings I have shown several embodiments of my invention, including my machine itself as well as individual parts thereof, which are all intended to be illustrative only, and not limiting. In this showing:

Figure 1 is a side elevational view of one adaptation of my machine;

Figure 2 is a section on line 2—2 of Figure 1;

Figure 3 is a front elevational view of the casing end, with the door removed, of the adaptation of my machine shown in Figure 1;

Figure 4 is a section, in fragmentary form, on an enlarged scale, on line 4—4 of Figure 3;

Figure 5a is a front elevational view of the door of the adaptation of my machine shown in Figure 1 as well as of the adaptation shown in Figure 6 below;

Figure 5b is a front elevational view, in fragmentary form, on an enlarged scale, showing detail of a door fastening device for bottom edge of door shown in Figure 5a;

Figure 5c is a section on line 5c—5c of Figure 5b;

Figure 6 is a side elevational view of a second adaptation of my machine;

Figure 7 is a section on line 7—7 of Figure 6;

Figure 8 is a front elevational view of the casing end, with the door removed, of the adaptation of my machine shown in Figure 6;

Figure 9a is a plan view of a door suspension applicable to the adaptations of my machine shown in Figure 1 and in Figure 6;

Figure 9b is a front elevational view of the door suspension shown in Figure 9a;

Figure 10 is a front elevational view of a fragmentary portion of a door, similar to the door shown in Figure 5a, but provided with a perforated extension for engagement with the hook of the door suspension shown in Figures 9a and 9b;

Figure 11 is a front elevational view of one type of a rotor element;

Figure 12 is a section on line 12—12 of Figure 11;

Figure 13 is a front elevational view of another type of a rotor element;

Figure 14 is a section on line 14—14 of Figure 13;

Figure 15 is a front elevational view of still another type of rotor element;

Figure 16 is a plan view of the uppermost vertical blade of Figure 15;

Figure 17 is a front elevational view of still another type of rotor element;

Figure 18 is a section on line 18—18 of Figure 17;

Figure 19 is a plan view of still another type of rotor element;

Figure 20 is a plan view of still another type of rotor element;

Figure 21 is a front elevational view of a circular saw;

Figure 22 is a section on line 22—22 of Figure 21;

Figure 23 is a fragmentary view of Figure 21 on an enlarged scale, showing an individual tooth;

Figure 24 is similar to Figure 23, except that the tooth is shown in perspective;

Figure 25 is a front elevational view in fragmentary form of one variety of an inserted tooth circular saw;

Figure 26 is an enlarged front elevational view of the tooth used in the circular saw of Figure 25;

Figure 27 is a front elevational view in fragmentary form of another variety of an inserted tooth circular saw;

Figure 28 is an enlarged front elevational view of the tooth used in the circular saw of Figure 27;

Figure 29 is a front elevational view in fragmentary form of still another variety of an inserted tooth circular saw;

Figure 30 is an enlarged front elevational view of the tooth used in the circular saw of Figure 29;

Figure 31 is a front elevational view in fragmentary form of still another variety of an inserted tooth circular saw;

Figure 32 is an enlarged front elevational view of the insert used in the circular saw of Figure 31;

Figure 33 is a section, in fragmentary form, on line 33—33 of Figure 31;

Figure 34 is an enlarged view in perspective of a tooth, such as used in the circular saw of Figure 25, tipped with very hard material;

Figure 35 is a view of an enlarged fragmentary portion of the circular saw shown in Figure 21, showing one position of a jet;

Figure 36a is also a view of an enlarged fragmentary portion of the circular saw shown in Figure 21, showing another position of a jet;

Figure 36b is a section on line 36b—36b of Figure 36a;

Figure 37a is also a view of an enlarged fragmentary portion of the circular saw shown in Figure 21, showing still another position of a jet;

Figure 37b is a section on line 37b—37b of Figure 37a;

Figure 38a is a fragmentary plan view of a circular saw with teeth sloping back at an angle from one side of the leading radial surface;

Figure 38b is a fragmentary elevational view on line 38b—38b of Figure 38a, in perspective, showing the teeth of Figure 38a;

Figure 38c is an enlarged fragmentary plan view of the circular saw of Figure 21;

Figure 39a is a front elevational view of the saw tooth of Figure 23 and a radial jet, showing effect of windage;

Figure 39b is a front elevational view of the saw tooth of Figure 23 and a jet slightly less than radial toward the oncoming tooth, also showing effect of windage;

Figure 40 is a view of an enlarged fragmentary portion of the circular saw shown in Figure 21, with nozzles positioned adjacent thereto;

Figure 41a is a front elevational view of a device for adjusting a nozzle radially, portions being broken away and a portion being shown in section;

Figure 41b is a front elevational view similar to Figure 41a, showing further detail, portions being broken away;

Figure 41c is a side elevational view of Figure 41b, in part cross sectional, portions being broken away, showing further detail;

Fig. 42 is a view in perspective of another de-

vice for adjusting a nozzle radially, a portion being broken away;

Figure 43 is a fragmentary longitudinal axial sectional view of a fitting for a tube with a flared end;

Figure 44a is a longitudinal sectional view of a nozzle;

Figure 44b is a view, from the orifice end, of the nozzle of Figure 44a;

Figure 45 is a sectional view in fragmentary form of a nozzle and feed device;

Figure 46 is a sectional view in fragmentary form of another type of nozzle and feed device.

In the drawings, similar numerals indicate like parts. A part designated by a numeral followed by a prime (') is a duplicate of the part designated by said numeral. In all figures where it is shown in connection with a rotor element, a curved arrow indicates the direction of rotation of the rotor element.

To describe my machine itself, I shall first consider Figure 1, which illustrates the first adaptation of my machine, referred to above, in which the problem of wear on the striking surfaces may be taken care of either by the employment of extremely hard or tough substantially wear resistant material for the striking surfaces or leading faces thereof, or by the use of replaceable striking surfaces which may be replaced when worn. 50 is the base (preferably of cast iron) of the machine of which 55 represents one of two extensions. Feet 56 of casing 59 are mounted on extensions 55, and rotor element 72 (not shown here but shown in Figure 3) in casing 59 is rotated by means of shaft 54, mounted in bearings 53 and 53', connected through flexible coupling 52 to, and driven by motor 51. Gland 57, attached to back plate 60 of casing 59 by cap screws 58, and provided with packing (not shown), maintains a seal between back plate 60 and shaft 54. Elbow fitting 67 screwed on to pipe nipple 66 which connects into conduit 78 (not shown here but shown in Figure 3) inside casing 59, carries a supply of liquid or slurry to conduit 78. Door 61, provided with handles 62, is held tightly against casing 59 by swing bolts 64 and 64', swinging on cap screws 63 and 63', engaging slots 182 and 182', and tightened in place by wing nuts 65 and 65'. For purposes of simplicity and clarity in the drawings, only two sets of slots 182 and 182', swing bolts 64 and 64', and associated parts are shown, but actually there are many more of these, substantially equally spaced, extending around the periphery of door 61 and casing 59, except at the bottom, where the fastening device shown in Figures 5b and 5c (to be described later) is used in their stead. Cap screws 65 and 65' fasten conduit 78 to back plate 60 by means of feet 200 (see Figure 4).

Figure 2 shows the rear view of the casing end of the machine shown in Figure 1, with shaft 54 projecting through gland 57 of back plate 60 of casing 59, and pipes 68 and 68' connecting into elbow fittings 67 and 67'. Certain other of the numbered parts described under Figure 1 are also shown, as well as parts 69 and 70 described under Figure 3 below. Figure 3, the front view of the casing end of the machine shown in Figure 1, with the door removed, shows rotor element 72, preferably of the type having striking surfaces or leading faces thereof of very hard or tough material, or of the type having replaceable striking surfaces, and conduit 78 supplying a plurality of nozzles 81 through pipe

nipples 79 and pipe couplings 80. Nozzles 81 are preferably so placed with respect to rotor element 72 that their longitudinal axes lies in the central plane of rotation of rotor element 72. 5 If conduit 78 were properly spaced from the periphery of rotor element 72, it would be possible 10 for nozzles 81 to be screwed directly into conduit 78, thus eliminating pipe nipples 79 and pipe couplings 80, but as this would leave but little space between conduit 78 and the periphery of rotor element 72, this is not my preferred arrangement. The location of conduit 78 within casing 59 is a convenient but not a necessary location in this adaptation of my machine, as, if 15 desired, conduit 78 may be made a part of casing 59 or located outside of casing 59, nozzles 81 being suitably connected to conduit 78. Rotor element 72 comprises disc 71 and striking surfaces 73, and is firmly affixed to outer end 74 of shaft 54 by means including safety collar 77, washer 76 and nut 75. The details of this assembly, including parts not shown in Figure 3, are shown in Figure 45 and will be described later. Casing 59 is provided with flange 69 to which is attached outlet duct 70. There is a large opening (not shown) in plate 84, the bottom of casing 59, and a corresponding opening in flange 69, both of which openings communicate directly with the interior of outlet duct 70, by means of which casing 59 is drained. Gasket 83, held in place by retaining strip 82, provides a tight seal between casing 59 and door 61 (not shown here but shown in Figure 5a) when door 61 is in place. Figure 4 shows a sectional view 30 of conduit 78, to which is attached foot 200, one of a plurality of feet by which conduit 78 is securely attached by means of cap screws 85 to back plate 60 of casing 59. Figure 4 also shows rotor element 72, conduit 78, nozzle 81 and associated parts. In operation of the adaptation of 35 my machine shown in Figures 1 to 4, a preferably continuous supply of liquid or slurry is delivered under pressure into conduit 78 by pipes 68 and 68', and passes out, by means of pipe nipples 79 and pipe couplings 80, through nozzles 81, as jets (not shown here), whereupon the jets are struck by the striking surfaces 73 of the rotor element 72 as it rotates, and the liquid or slurry which has been struck discharges preferably continuously from casing 59 through outlet duct 70.

Figure 5a shows door 61 which fits against the front of casing 59 as a removable closure. Into slots 182 and 182' of door 61, fit swing bolts 64 55 and 64' of casing 59, which are held securely by means of wing nuts 65 and 65' (all being shown in Figure 1). Handles 62 and 62' are of assistance in handling door 61. Figures 5b and 5c show the detail of the door fastening device for the bottom edge of door 61. As previously explained, door 61 is held to casing 59 by a substantial number of swing bolts 64, disposed around the periphery of casing 59, except at the bottom. There is not room for swing bolts at that point because of 60 outlet duct 70, and hence the fastening device shown in Figures 5b and 5c is preferably employed. In these figures, as before, 84 is the bottom plate of casing 59 to which is attached flange 69, and retaining strip 82 which retains gasket 83. In the forward extending portion of flange 69 are drilled two holes 88 and 88' into which fit lugs 88 and 88' of fastening bar 201. Thumb screws 86 and 86' are screwed through threaded holes 87 in fastening bar 201 against bottom portion 65 of door 61. By tightening thumb screws 86 70

and 86', bottom portion of door 61 is caused to bear snugly against gasket 83. This arrangement, in connection with swing bolts 64, causes door 61 to make a liquid tight joint against gasket 83 of casing 59. When it is desired to release door 61, wing nuts 65 and 65' are loosened, and swing bolts 64 and 64' swung out of slots 182 and 182' (Figure 5a) of door 61, then thumb screws 86 and 86' are loosened, fastening bar 201 lifted out of place, thereby disengaging lugs 88 and 88' from holes 89 and 89', and door 61 may then be removed, or swung out of place (as described under Figures 9a, 9b and 10 below).

The adaptation of my machine shown in Figures 6 to 8 differs from that shown in Figures 1 to 4 primarily in that conduit 78a in Figure 6 is located on the rear and outside of casing 59 instead of inside as is conduit 78 in Figure 1, that nozzles 81 are adjustable (not shown in Figures 6 and 7, but shown in Figure 8), and that rotor element 72 (not shown in Figures 6 and 7, but shown in Figure 8) is preferably of the integral tooth type which is subjected to periodical machining or grinding to restore the general contour of the striking surfaces, and is thereby progressively decreased in diameter. (Rotor elements with the same type of striking surfaces as described for use in the adaptation of my machine shown in Figures 1 to 4 may of course, if desired, be used alternatively in the adaptation of my machine I am now describing.) The location of conduit 78a outside of casing 59 is a convenient but not a necessary location in this adaptation of my machine, as, if desired, conduit 78a may be made a part of casing 59 or located inside of casing 59. The other numbered parts shown in Figure 6 are similar parts to those shown in Figure 1, with the exception of 68 and 90 (not shown in Figure 1), 68 being a pipe connecting into elbow fitting 67, and 90 being the flanged plate of conduit 78a, attached to back plate 60 of casing 59. Figure 7 shows the rear view of the casing end of the adaptation of the machine shown in Figure 6, while Figure 8 shows the front view of the casing end of the machine. Considering Figures 7 and 8 together, in operation a preferably continuous supply of liquid or slurry is delivered under pressure into conduit 78a by pipes 68 and 68', connected thereto by elbow fittings 67 and 67' and pipe nipples 66 and 66', and fed from conduit 78a through flexible hoses 93, connected into conduit 78a through back plate 60 of casing 59. From flexible hoses 93, the liquid or slurry feeds through T fittings 95 to nozzles 81, which are adjustable radially in respect to rotor element 72, and from nozzles 81 the liquid or slurry issues as jets (not shown here). Striking surfaces 73 of rotor element 72 as it rotates strike the jets of liquid or slurry issuing from nozzles 81, and the liquid or slurry that has been struck discharges preferably continuously from casing 59 through outlet duct 70. Nozzles 81 are preferably so placed with respect to rotor element 72 that their longitudinal axes lie in the central plane of rotation of rotor element 72. As the diameter of rotor element 72 is decreased by periodic grinding, nozzles 81 may be advanced radially toward the center of rotation of rotor element 72 to maintain any desired distance between the orifice end of nozzles 81 and the periphery of rotor element 72. This may be accomplished by loosening lock nuts 98 on threaded rods 94, then loosening adjusting nuts 97, sliding threaded rods 94 the appropriate distance toward rotor element 72 through the holes in which they fit in ring 96, tightening ad-

justing nuts 97 and then tightening adjusting nuts 97' and lock nuts 98. In Figure 7, flanged plate 90 of conduit 78a is attached to back plate 60 of casing 59 by cap screws 91 and 91'. Cap screws 92 and 92' fasten ring 96 (shown in Figure 8) to back plate 60 of casing 59 by feet 181 (not shown here but shown in Figure 41c to be described below) attached to ring 96. Other numbered parts shown in Figures 7 and 8 not already specifically referred to in the discussion of those figures and Figure 6, have already been discussed in connection with Figures 1 to 4.

It is, of course, possible to convert the adaptation of my machine shown in Figures 1 to 4 into a sort of an adjustable nozzle type machine by the simple expedient of providing several sets of pipe nipples 79, or pipe couplings 80, or even nozzles 81, (all shown in Figure 3), of different lengths, substituting successively the longer lengths for the shorter lengths as required, and thus in effect providing nozzles adjustable radially in respect to the rotor element.

Figures 9a and 9b show a suspension device for the door shown in Figure 10. This device provides a means for handling a heavy door more conveniently, and may be mounted on the top of casing 59 in either adaptation of my machine shown above. The door is suspended from the suspension device and after loosening the fastenings which hold the door in place, the door may be swung to one side of casing 59, out of the way. In Figures 9a and 9b, plate 99 is supported by channels 110 and 110' on one end of the top plate of casing 59. At the central rear portion of plate 99 is a hole through which extends upwardly bolt 107 on to which is screwed, above the level of plate 99, spacer collar 109. Bolt 107 further extends up through a hole in arm 101, and, on the further end of bolt 107 above arm 101, is fitted thrust bearing 104' and finally nut 108. Bolt 107 serves as the pivot about which arm 101 may swing in a restricted arc in a horizontal plane. At approximately the middle point of the bottom side of arm 101 is fastened bracket 106 which positions and provides bearings for the journal ends of crowned rollers 105 and 105', by which arm 101 is supported. Rollers 105 and 105' are adapted to roll in an arc, with bolt 107 as a center, on the upper face of plate 99 when the front end of arm 101 is swung in the arc indicated by the curved arrow shown in Figure 9a. Hook 102, threaded at its upper end, extends upwardly through a hole in the front extremity of arm 101, through thrust bearing 104 and finally nut 103. Door 61 of Figure 10 is provided with extension 112 perforated with hole 111 into which fits the bottom (hooked) end of hook 102, and door 61 is thereby suspended therefrom. Hook 102 may be adjusted as to length by nut 103 so that the bottom edge of door 61 just clears flange 69 of casing 59 (shown in Figures 5b and 5c). When door 61 is to be used as closure for casing 59, arm 101 from which door 61 is suspended by hook 102 is swung into position shown in Figure 9a, and door 61 is then ready to be fastened into place by swinging swing bolts 64 and 64' into slots 182 and 182' and tightening wing nuts 65 and 65', and by employing the fastening bar device as shown in Figures 5b and 5c, tightening thumb screws 86 and 86' thereof. When it is desired to open door 61, wing nuts 65 and 65' are loosened, swing bolts 64 and 64' are swung back out of slots 182 and 182', thumb screws 86 and 86' (of Figures 5b and 5c) are loosened and fastening bar 201

is removed. Then door 61, on being pulled forward by grasping handles 62 and 62' (Figure 5a), and following the direction of the curved arrow shown in Figure 9a, will arrive at a position at the side of casing 59, and substantially parallel to the side of casing 59, so that easy access may be had to the inside of casing 59 and the parts therein. Stop 100 acts to limit the swing of arm 101 by obstructing further travel of roller 105. Thrust bearings 104 and 104', as well as rollers 105 and 105', enable arm 101 and door 61 to be easily swung around, whereby door 61 may be readily opened by one man.

In order to operate either adaptation of my machine, shown respectively in Figures 1 to 4, and Figures 6 to 8, door 61 is closed and fastened against casing 59, the electric current is switched on motor 51, which causes rotor element 72 to revolve at a high rate of speed, and, preferably after rotor element 72 has attained full speed, liquid or slurry is delivered preferably continuously into conduit 78 (or 78a as the case may be) under pressure, from whence it discharges as jets through nozzles 81 and is struck by striking surfaces 73 of rotor element 72. The liquid or slurry after being struck goes to the bottom of casing 59 and is discharged by gravity from the casing through outlet duct 70.

Referring to the drawings, in respect to examples of various illustrative types and designs of rotor element which I may use in my machine, in Figures 11 and 12, 71 represents the central portion such as the disc of rotor element 72, adapted to be rotated in either direction, provided with central opening 113 for attachment to shaft 54, to which it is secured by means of a key (not shown) in keyway 114. 115 represents the individual members of a series of projections, serrations, or teeth on the periphery of disc 71, which constitute the striking surfaces of rotor element 72. While the faces of 115, as shown, lie substantially in radial planes at right angles to the planes of rotation of rotor element 72, which is their preferred location, they may, if it is desired, lie in planes at an angle to such radial planes. In Figures 13 and 14, disc 71 of rotor element 72, adapted to be rotated in either direction, with central opening 113 for attachment to shaft 54 and keyway 114, is provided with projections of which 116 is an individual member of a series arranged on one end face of disc 71 near its periphery, which constitute the striking surfaces of rotor element 72. As was the case in Figures 11 and 12, here again the faces of 116 lie in radial planes at right angles to the planes of rotation of rotor element 72, which is their preferred location, but they may, if it be desired, lie in planes at an angle to such radial planes.

In Figure 15, disc 71 of rotor element 72, with central opening 113 for attachment to shaft 54 and keyway 114, is provided with blade 117, an individual member of a series, a plan view of which is shown in Figure 16, with a crescent-like cross section similar to the blades of a steam turbine wheel, moving in the direction of the adjacent arrow, and arranged on the periphery of disc 71, radially as shown, which is the preferable position, which constitute the striking surfaces of rotor element 72. In Figures 17 and 18, disc 118 and 118' of rotor element 72, adapted to be rotated in either direction, provided with central opening 113 for attachment to shaft 54 and keyway 114, are two in number, forming an annular space through which pins 119 and 119' pass

into discs 118 and 118'. Hammers 120 and 120', pivoted on pins 119 and 119', swing out preferably to substantially radial positions when discs 118 and 118' rotate, and constitute the striking surfaces of rotor element 72. In Figure 19, disk 71 of rotor element 72, adapted to be rotated in either direction, is provided with projections or teeth of which 121 is an individual member of a series disposed around the periphery of disc 71, which constitute the striking surfaces of rotor element 72, in this instance the faces of projections 121 being at an angle to the radial planes at right angles to the planes of rotation of rotor element 72. In Figure 20, disc 71 of rotor element 72, rotated preferably in the direction of the adjacent arrow, is provided with striking surfaces, in this case projections, of which 122 is an individual member of a series disposed around the periphery of disc 71, in this instance being of V shape cross section. Rotor elements of the designs shown in Figures 15, 16, 19 and 20 are usually somewhat less efficient than the designs shown in the other figures.

In Figures 21 and 22, rotor element 72 is a circular saw, with disc 71, central opening 113 for attachment to shaft 54 and keyway 114, provided with striking surfaces, in this case teeth, of which 123 is an individual member of a series disposed around the periphery of disc 71. In Figure 23 and Figure 24 (in perspective), an individual tooth 123 of circular saw 72 of Figure 21 is shown, moving in the direction of the adjacent arrow. Leading face 123 of tooth 123 lies substantially in a radial plane at right angles to the planes of rotation of circular saw 72. Rear face 124 of tooth 123, as shown, slopes away from leading face 123 at an angle of approximately 45°. Rotor element 72 with teeth 123 of Figures 21 to 24, i. e. a circular saw with teeth of the type described, is my preferred rotor element for use in the second adaptation of my machine shown in Figures 6 to 8, wherein adjustable type nozzles are used.

The rotor element which I employ in the practice of my invention is, as previously indicated, subject to wear in respect to its striking surfaces. This is particularly the case when operating on material such as a slurry. Where the striking surfaces are integral with, and are machined directly from, the rotor element, if the rotor element itself is replaced when the striking surfaces are worn, this procedure is very expensive. The rotor element may, however, as stated above, where adjustable type nozzles are used as in the second adaptation of my machine, be remachined or the like to smaller diameter, which is an economical practice. Another method of handling the problem of wear is to make the striking surfaces themselves, or the teeth, separable and renewable.

In respect to inserted or renewable teeth circular saws suitable for my use, I shall now give several examples. Here again I prefer to have the leading faces of the teeth radial or "substantially radial." In Figure 25, one type of an inserted tooth (or inserted "point" as they are sometimes called) circular saw is shown, illustrative of this variety of saw. Disc 71 of rotor element 72 (in this instance an inserted tooth circular saw), with central opening 113 for attachment to shaft 54 and keyway 114, is provided with inserted tooth 125, an individual member of a series inserted in the periphery of disc 71. Tooth 125 is positioned in disc 71 by a groove (not shown) milled in the edge of the tooth for the distance the tooth is inserted into disc 71, which

cooperates with a tongue (not shown) in the edge of recess 126 of disc 71. Tooth 125 is held from sliding out of place by rivet 127, which, as shown, extends for half its cross-sectional area into a properly shaped depression in tooth 125 and for the other half into a similarly shaped depression in disc 71. Tooth 125 and rivet 127 are replaceable. Tooth 125 may be ground if desired when worn, and when worn out may be replaced by new tooth 125. Figure 26 shows individual tooth 125 used in circular saw 72 of Figure 25, moving in the direction of the adjacent arrow. In Figure 27 is shown another type of an inserted tooth circular saw. Disc 71 of rotor element 72 (in this instance, also, an inserted tooth circular saw), with central opening 113 for attachment to shaft 54 and keyway 114, is provided with inserted tooth 128, an individual member of a series inserted in the periphery of disc 71. Tooth 128 is positioned in disc 71 by a groove (not shown) milled in the entire edge of the tooth with the exception of its leading edge beyond disc 71 and the edge on its outer end. This groove cooperates, in the lower part of the leading edge of tooth 128, with a tongue (not shown) in the edge of recess 129 of disc 71, and tooth 128 is held in place by wedge 130 which is provided with a tongue (not shown) to fit in the groove in the rear edge of tooth 128, a groove (not shown) in the rear edge of wedge 130 cooperating with the tongue on the rear edge of recess 129 of disc 71. By tapping down wedge 130, tooth 128 may be released. Conversely by tapping wedge 130 from its lower end towards the periphery of disc 71, tooth 128 may be tightened into place. Both tooth 128 and wedge 130 are replaceable when worn. Tooth 128 may be ground if desired when worn, and when worn out may be replaced by new tooth 128. Ordinarily wedge 130 is not worn appreciably and will outlast a number of tooth 128 replacements. Figure 28 shows the individual inserted tooth 128 used in circular saw 72 of Figure 27, moving in the direction of the adjacent arrow.

In Figure 29 is shown still another type of an inserted tooth circular saw. Disc 71 of rotor element 72 (in this instance, again, an inserted tooth circular saw), with central opening 113 for attachment to shaft 54 (not shown) and keyway 114, is provided with inserted tooth 131, an individual member of a series inserted in the periphery of disc 71. Tooth 131 is positioned in disc 71 by a tongue (not shown), milled along the portion of tooth 131 adjacent to holder 133, cooperating with a groove in the edge of holder 133, said groove (not shown) extending around the convex edge of holder 133 where it cooperates with a tongue (not shown) milled in the edge of recess 132 of disc 71. Tooth 131 is also provided with a groove (not shown) along its edge adjacent to disc 71 where it cooperates with the tongue milled in the edge of recess 132. Holder 133 is provided with an opening 134 into which may be fitted a tool (not shown) whereby holder 133 may be disengaged from disc 71 by a circular motion which removes it from recess 132, at the same time releasing tooth 131. Tooth 131 is replaceable when worn by another tooth of similar design, which in turn is held in position by holder 133. Tooth 131 may be ground if desired when worn, and when worn out may be replaced by new tooth 131. Ordinarily holder 133 is not worn appreciably and will outlast a number of tooth replacements. Figure 30 shows individual tooth 75

131 used in circular saw 72 of Figure 28, moving in the direction of the adjacent arrow.

In Figure 31 is shown still another type of an inserted tooth circular saw. This is, however, of a slightly different type from those previously illustrated in that each insert may contain, instead of one tooth, a plurality of teeth if desired, and also each insert may be ground substantially to the limit of the insert before discarding and replacing. This type of inserted tooth saw, if the inserted teeth are not to be ground, may be used in the first adaptation of my machine, namely where fixed type nozzles are used, but if the teeth are to be ground, which reduces the diameter of the saw somewhat, the saw is preferably used in the second adaptation of my machine, namely where adjustable type nozzles are used. In Figure 31, disc 71 of rotor element 72 (in this instance, again, as stated, a type of inserted tooth circular saw), with central opening 113 for attachment to shaft 54 and keyway 114, is provided with insert 183, an individual member of a series inserted in (that is to say, in this case affixed to) the periphery of disc 71. Insert 183 is provided with one or more teeth 184, four in number in the example illustrated, and is fastened to disc 71 by means of eyelets 185 inserted in holes 186 in insert 183 and extending through the corresponding holes in disc 71. After insertion, the unexpanded ends of eyelets 185 are slightly expanded. Holes 186 of both insert 183 and disc 71 are preferably countersunk at their outer ends, and eyelets 185 thus firmly attach insert 183 to disc 71. Figure 32 shows an enlarged view of insert 183, with teeth 184 and countersunk holes 186. The dotted line 187 indicates a shoulder on the rear side of insert 183, which fits snugly over cooperating projection 188 of disc 71. This is shown clearly in Figure 33, a sectional view, where it is seen that the shoulder 187 abuts projection 188 of disc 71, and likewise projection 189 of insert 183 abuts shoulder 190 of disc 71.

Figure 34 illustrates, in perspective, tooth 186, such as used in circular saw 72 of Figure 25, moving in the direction of the adjacent arrow, and similar to tooth 125, except that it is provided with a very hard tip or facing 186.

As to the thickness of circular saws, the circular saws I have used have included saws $\frac{1}{8}$ ", $\frac{1}{4}$ " and $\frac{5}{16}$ " thick. Practically, for efficient operation, the saw, or the teeth in inserted tooth saws, should preferably be at least as thick as the diameter of the jet in order to hit the entire jet and not merely cut through it longitudinally, and to be most effective should be somewhat thicker so as to allow for any endwise play in the bearings, any possible vibration in the saw, any broadening effect of the teeth on the jet, or any increase in diameter of the jet due, for example, to windage. It is well to provide a saw, or the teeth in an inserted tooth saw, of a thickness of approximately two to four times the diameter of the jet (or nozzle channel), although the thickness may be greater if desired. Circular saws, or the teeth in inserted tooth circular saws, from $\frac{1}{4}$ " to $\frac{3}{8}$ " in thickness will be found adequate in most cases.

In respect to nozzle placement in my machine, a variety of positions may be employed. For example, in one placement of the nozzles, the nozzle or nozzles may be so arranged that the jet or jets of liquid or slurry issuing therefrom may be directed against the teeth or other striking surfaces of the rotor element, (the striking surfaces having their leading faces preferably on radial planes, and at right angles to the planes of rota-

tion, of the rotor element), the jet or jets being preferably substantially in a plane of rotation of the rotor element, (the longitudinal axis of the jet or jets being preferably in the central plane of rotation of the rotor element), and as nearly tangential to the rotor element and as nearly at right angles to the leading faces of its striking surfaces at the point of contact as may be feasible, and travelling in a direction opposed to that of the rotation of the rotor element. The area of contact of the jet and the striking surface is substantially the cross sectional area of the jet. In a second placement of the nozzle, the jet or jets of liquid or slurry may issue from a nozzle or nozzles so situated that the jet or jets are in a plane or planes which may be substantially at right angles to the planes of rotation of the rotor element and preferably directed in a direction substantially at right angles to the planes of rotation of the rotor element, in such a position that the striking surfaces (preferably positioned as described under the description of the previous nozzle placement) of the rotor element strike the jet or jets. In this case the contact of the jet and the striking surface is on the cylindrical surface of the jet (i. e. in the case of a jet issuing from a nozzle having a cylindrical channel). In a third placement of the nozzles, and this is my preferred placement thereof, the nozzle or nozzles, while as in the second placement they may be in a plane or planes which may be substantially at right angles to the planes of rotation of the rotor element, are so situated that the jet or jets issuing therefrom may be in a plane of rotation of the rotor element, and preferably the longitudinal axis of the jet or jets is in the central plane of rotation of the rotor element. The jet or jets are directed from preferably just beyond the periphery of the rotor element in a direction preferably substantially radial to the rotor element and towards its center of rotation, and, when struck, are preferably substantially parallel to the leading face of its striking surface or surfaces (which again are preferably positioned as described under the description of the first nozzle placement). In this third nozzle placement, the contact of the jet and the striking surface is similar to that in the second placement just described, namely, on the cylindrical surface of the jet.

The first nozzle placement referred to above is illustrated in Figure 35, which is an enlarged fragmentary portion of circular saw 72 shown in Figure 21. In Figure 35, disc 71 of circular saw 72 is provided with tooth 73, which strikes jet 137, which issues from nozzle 81 (shown in fragmentary form) in the direction of the adjacent arrow. Nozzle 81 is fixedly positioned while circular saw 72 rotates in a direction toward nozzle 81. When tooth 73 strikes jet 137 there is naturally a spattering of the end of the jet. This spattering is not shown. The second nozzle placement referred to above is illustrated in Figure 36a, which, like Figure 35, is an enlarged fragmentary portion of circular saw 72 shown in Figure 21. In Figure 36a, disc 71 of circular saw 72 is provided with tooth 73, which strikes the end portion of jet 137 issuing from nozzle 81. Nozzle 81 is fixedly positioned while circular saw 72 rotates in the direction of the arrow. The planes of rotation of circular saw 72 are substantially at right angles to the longitudinal axis of jet 137. When tooth 73 strikes jet 137 there is naturally a spattering of the end portion of the jet. This spattering is not shown. Figure 36b is a section

on line 36b—36b of Figure 36a. In Figure 36b, as in Figure 36a, disc 71 of circular saw 72 is provided with tooth 73 which strikes the end portion of jet 137 which issues from nozzle 81 (shown in fragmentary form) in the direction of the adjacent arrow. The distance jet 137 advances in front of the face of tooth 73 before being struck depends upon the relative speeds of circular saw 72 and jet 137. The third nozzle placement referred to above, my preferred placement, is illustrated in Figure 37a, which, like Figures 35 and 36a, is an enlarged fragmentary portion of circular saw 72 shown in Figure 21. In Figure 37a, disc 71 of circular saw 72 is provided with tooth 73, which strikes the end portion of jet 137, which issues from nozzle 81 (shown in fragmentary form) in the direction of the adjacent arrow. The distance jet 137 advances in front of the face of tooth 73 before being struck depends on the relative speeds of circular saw 72 and jet 137. Nozzle 81 is fixedly positioned while circular saw 72 rotates in the direction of the curved arrow. The tangent to circular saw 72 at its point of contact with jet 137 is substantially at right angles to the longitudinal axis of jet 137, the longitudinal axis of jet 137 lying in a plane of rotation, and preferably in the central plane of rotation, of circular saw 72. When tooth 73 strikes jet 137 there is naturally a spattering of the end portion of the jet. This is not shown. Figure 37b is a section on line 37b—37b of Figure 37a. In Figure 37b, as in Figure 37a, disc 71 of circular saw 72 is provided with tooth 73 which strikes the end portion of jet 137 which issues from nozzle 81, the longitudinal axis of jet 137 lying substantially in the central plane of rotation of circular saw 72. The jets shown in Figures 35, 36a, 36b, 37a, and 37b are intended in those figures to be of substantially circular cross section, but of course they may be of any other cross sectional pattern desired.

The first nozzle placement described above, and shown in Figure 35, namely the nearly tangential one, although fairly satisfactory, is not completely so, because as will be apparent, it is not possible to arrange the nozzle to deliver a jet exactly tangentially in order that the advancing tooth may strike it exactly at a right angle to the leading face of the tooth (unless the number of teeth be relatively limited) because of the interference with the jet by the teeth preceding the one which would otherwise hit the jet at a right angle.

Cross reference is hereby made to my copending application Serial No. 436,196, filed March 25, 1942, now Patent No. 2,383,509, dated August 28, 1945.

The second nozzle placement described above, and shown in Figures 36a and 36b, namely, the one in which the jet or jets are directed substantially at right angles to the planes of rotation of the saw, near the periphery of the saw, also gives fairly satisfactory results, but has certain disadvantages particularly when using a saw with teeth cut in the ordinary manner.

The third nozzle placement described above, and shown in Figures 37a and 37b, namely, the radial one, is the best from the standpoint of convenience, and, except when using a saw with the special shaped teeth shown in Figures 38a and 38b, is also the best from the standpoint of efficiency. In this third nozzle placement, the jet is cut off by the advancing tooth, the part cut off being struck a blow at right angles to the longitudinal axis of the jet, and the same situation

is repeated by each succeeding tooth. The entire jet as it advances is thus hit portion by portion, no part escapes being hit, and the jet being radial is struck by the radial face of the tooth in the direction of travel of the advancing tooth which provides the most effective blow. For these reasons, and also because of the ease of adjustment of the nozzle to progressively smaller saw diameters when employing the second adaptation of my machine, I prefer this third nozzle placement.

There is a slight modification of this third nozzle placement, i. e. the radial nozzle placement, which may be used if desired, and that is a nozzle placement which delivers a jet which has a direction at a slight angle to the radial toward the leading faces of the oncoming teeth. The object of this is so that the jet may be swerved back toward a radial position by the windage of the saw. If the jet is radial to start with it may be swerved slightly from the radial by the windage, but if it is slightly less than radial toward the oncoming teeth to start with, it may be swerved by the windage substantially into a radial direction at the point where it is hit by the teeth, and thus the efficiency of the operation will be improved. This situation is illustrated in Figure 39a, which shows circular saw tooth 73 of Figure 23 advancing in the direction of the adjacent arrow, with radial leading face 123, and nozzle 81 (shown in fragmentary form) in substantially radial position, from which, in the direction of the adjacent arrow, issues jet 137 originally substantially radial, but, as it advances, swerved slightly from a radial direction by the air current created by the rotating saw, i. e. the "windage," so that when hit by tooth 73, jet 137 is not travelling radially. Figure 39b shows circular saw tooth 73 of Figure 23, advancing in the direction of the adjacent arrow, with radial leading face 123, and nozzle 81 (shown in fragmentary form) in a position slightly less than radial toward the oncoming tooth, from which, in the direction of the adjacent arrow, issues jet 137, originally slightly less than radial toward the oncoming tooth, but as it advances swerved slightly by the windage into substantially a radial direction. The swerving effect of the windage on the jet is greatly exaggerated in Figures 39a and 39b for purposes of illustration, as actually it is but slight at the jet speeds I prefer to employ and at the nozzle distance from the saw periphery at which I prefer to operate. In addition to the swerving effect on the jet, the windage has a dispersing effect thereon (not shown), which tends to flatten out the jet, break it into streams or drops, and deflect these away from the saw teeth. This effect is, however, negligible under the jet speeds and nozzle distances at which I prefer to operate. Thus although I may employ nozzles placed so that the jets issue in a slightly less than radial direction toward the oncoming teeth, I prefer the radial placement as being substantially as efficient under the conditions I prefer to operate and as being a somewhat simpler arrangement mechanically.

The jet or jets issuing from the nozzle or nozzles of my machine may have any desired speed, e. g., as low as 23 feet per second as shown in my above referred to application Serial No. 718,649, Table X, but in respect to speed of jet, there is a fundamental consideration which should be taken into account, namely, the distance the jet will travel radially while the saw moves forward one tooth. As an example, assuming the distance from point to point (i. e. tooth

to tooth) of the circular saw to be .5", a convenient distance to use in a circular saw of the integral tooth type which I may employ, and assuming the speed of the issuing jet to be 100 feet per second, and that of the periphery of the saw to be 460 feet per second, the jet thus travels 21.7% as fast as the saw, travelling radially about .11" while the saw travels peripherally .5". Thus the length of the cylindrical jet cut off by each saw tooth is about .11" long. By a calculation similar to the above, it is found that with a jet speed of 186 feet per second the jet advances approximately .2" between teeth, while with a jet speed of 556 feet per second, it advances approximately .6". Inasmuch as the depth of the gullet between the teeth for a saw with teeth .5" from point to point is usually only about .375", and as the backs of the teeth usually slope down at an angle of approximately 45°, it is apparent that with a jet speed of 556 feet per second the jet hits at least part of the sloping back of the tooth between each two teeth, as well as probably the bottom of the gullet between each two teeth, about one third the total length of the jet between each two successive teeth hitting these surfaces and only about two-thirds of its length (limited to the depth of the gullet) being struck a blow by the oncoming tooth at right angles to the longitudinal axis of the jet. Thus it is apparent that the optimum effect to be obtained by the striking of the radial tooth faces against the jet is secured when the speed of the issuing jet is less than that which would bring the jet into contact with the back of the teeth or the bottom of the gullets. Within this limitation, the speed of the jet should preferably be great enough substantially to overcome the swerving and dispersing effects on the jet caused by the windage of the saw at the nozzle distance intended to be employed.

As previously indicated herein, I may use one nozzle or a plurality of nozzles, and from a practical standpoint I prefer to use as many nozzles as it is feasible to position conveniently around the periphery of the circular saw (or other rotor element) in order, among other reasons, to obtain adequate capacity of liquid or slurry delivered into the path of the teeth of the circular saw, taking into consideration the channel diameter of the nozzles employed. Figure 40 shows an enlarged fragmentary portion of circular saw 72 of Figure 21, with a plurality of nozzles arranged adjacent thereto. The leading faces of teeth 73, arranged on the periphery of disc 71 of circular saw 72, moving in the direction of the adjacent arrow, strike the end portions of jets 137 issuing in a substantially radial direction toward the center of rotation of circular saw 72 from nozzles 81 (shown in fragmentary form), in exactly the same manner as is illustrated for individual jet 137 and individual nozzle 81 in Figure 37a.

I have stated that, when using circular saws with integral teeth which are periodically ground such as for use in the second adaptation of my machine, the nozzles should preferably be adjustable radially in respect to the circular saw in order that they may be adjusted to compensate for the decrease in diameter of the saw due to grinding. This adjustable feature is shown in Figure 8 and has already been described. However there are some further details of this feature which I shall now discuss more fully. Figure 41a is further illustrative of the construction for adjusting nozzles radially shown in Figure 8, but in

enlarged view and showing more details. Jet 137 issues from nozzle 81 in the direction of the adjacent arrow, radially in respect to rotor element 72, in this case a circular saw, of which only one striking surface 73, in this case a tooth, is shown. Circular saw 72 moves in the direction of the arrow adjacent thereto. Nozzle 81 is preferably so positioned that the longitudinal axis of jet 137 is centered midway across the thickness of the saw (as in Figure 37b). Nozzle 81 is a steel pipe plug which has been drilled longitudinally with an appropriate size drill, and which is screwed tightly into the lower end of T fitting 95, into the other end of which is screwed threaded rod 94, with a pipe thread on the end screwed into the T fitting 95, so that a solid and tight connection may be made. Into the side outlet (facing forward in Figure 41a) of T fitting 95 is connected union hose coupling 142, to the other end of which is clamped flexible hose 93 (shown in fragmentary end view) by means of hose clamp 143. A supply of liquid or slurry is fed into a conduit (not shown here but corresponding for example to conduit 78a of Figures 6 and 7) which feeds the other end (not shown) of hose 93. Threaded rod 94 is slideable in hole 141 drilled in ring 96 (shown in fragmentary form). Ring 96 is suitably made from a bar of steel, of square or rectangular cross section, rolled, and welded into a continuous ring which surrounds the periphery of circular saw 72 and which is rigidly attached to back plate 60 of casing 59 (neither shown here, but shown in Figures 6 and 7) in which circular saw 72 rotates. Threaded rod 94 is held in place by adjusting nuts 97 and 97' and lock nut 98. By loosening both lock nut 98 and adjusting nut 97' the appropriate amount, threaded rod 94 may be advanced radially toward the center of rotation of circular saw 72, and when the proper adjustment has been made, threaded rod 94 may be fixed in place by tightening adjusting nuts 97 and 97', and held securely in that position by tightening lock nut 98. It will be apparent that if circular saw 72, of which 73 is a tooth, is ground and decreased in diameter, nozzle 81 may be advanced radially an appropriate amount to maintain a constant, or any desired distance, between the orifice end of nozzle 81 and the periphery of saw 72. Likewise in installing a new circular saw 72 of larger diameter than worn circular saw 72 of reduced diameter previously used, nozzles 81 may be retracted radially by appropriate adjustment of adjusting nuts 97 and 97' and lock nut 98, and then held at the desired position by tightening these nuts.

Figure 41b is a view of the nozzle adjustment construction shown in Figure 41a, but in Figure 41b hose 93, instead of being shown only in fragmentary end view, is shown completely in plan. In Figure 41b, in order not to confuse the drawing with detail, union couplings 142 and 142', and hose clamps 143 and 143', one of each for each end of hose 93, are not shown (these being shown in Figure 41c). As will be seen from Figure 41b, hose 93 is connected at one end into side outlet (facing forward in Figure 41b) of T fitting 95 and at the other end at back plate 60, shown in fragmentary form (of casing 59). Figure 41c is a side view of Figure 41b. In Figure 41c, back plate 60, conduit 78a and ring 96, among other parts, are shown in cross section. Conduit 78a is constructed of sides 179 and 179', rear plate 180 and flanged plate 90, secured to each other suitably by welding. Conduit 78a is ring shaped (this cannot be seen in Figure 41c, but is shown

in Figure 7), and into conduit 78a is introduced by suitable means such as a pump (not shown), through inlet nipples 66 and 66' (not shown here but shown in Figure 7), a supply of liquid or slurry for supplying nozzle 81 through hose 93. Flanged plate 90 of conduit 78a is attached to back plate 60 by cap screws 91 and 91'. Pipe nipple 178 is inserted through a hole in back plate 60, and screwed into a threaded hole in flanged plate 90 of conduit 78a to make a pressure tight connection, the other end of pipe nipple 178 being screwed into one end of union coupling 142'. Hose 93 is attached to the other end of union coupling 142' and held tightly in place by hose clamp 143'; and the other end of hose 93 is attached to the side outlet of T fitting 95 in a similar manner with union coupling 142, hose clamp 143, and pipe nipple 202. As will be apparent, in Figures 41b and 41c, the liquid or slurry travels from conduit 78a through pipe nipple 178 and hose coupling 142', through hose 93 in the direction of the adjacent arrow, through hose coupling 142 and pipe nipple 202, through T fitting 95 and out nozzle 81 as jet 137, in the direction of the arrow adjacent thereto. Threaded rod 94 is shown in Figure 41c in fragmentary form in order not to obscure the connection of hose 93 at its conduit end. Ring 96 (shown in cross section in Figure 41c) is positioned in respect to the back plate 60 by a series of spaced feet 181, suitably six in number (only one of which is shown) suitably welded on ring 96 and attached firmly to back plate 60 by means of cap screw 92, fitting through a hole in back plate 60, and being screwed into a threaded hole in foot 181. Ring 96 is thus firmly attached to back plate 60, threaded rod 94 is firmly fastened by adjusting nuts 97, 97' and lock nut 98 in ring 96, T fitting 95 is firmly secured to threaded rod 94, and thus nozzle 81, which is firmly secured in T fitting 95, is rigidly held in position in respect to tooth 73 of circular saw 72, but is adjustable radially in respect thereto. (Instead of using threaded rod 94, and adjusting nuts 97 and 97' and lock nut 98, the rod may, if desired, be made smooth so as to be a sliding fit in hole 141 of ring 96, be adjusted in position in hole 141, and held e. g. by a set screw inserted in an appropriate hole in the front side of ring 96 at right angles to hole 141.)

The radial nozzle adjustment shown in Figures 41a, 41b and 41c, provides a means for maintaining a flow of liquid or slurry from nozzle 81 throughout the entire range of adjustment of threaded rod 94, as when threaded rod 94 is advanced through ring 96, hose 93 is sufficiently long to take care of this advance, and when threaded rod 94 is retracted, hose 93 by bowing out slightly, adjusts itself to the new position. Figures 41a, 41b and 41c thus make clear one illustrative device by which a nozzle may be adjustable radially while means for supplying liquid or slurry thereto is maintained.

If the nozzles and nozzle attachments are accurately made, as is my customary practice, a radial adjustment such as shown in Figures 41a, 41b and 41c, is all that is required. But if not, it is desirable to have adjustment possible in all directions, so that any slight inaccuracy in machining or in the nozzles themselves may be allowed for, and the nozzles set to deliver the jets accurately in a substantially radial direction, in a plane of rotation of the saw, with the longitudinal axes of the jets centered midway across the thickness of the saw. Figure 42 illustrates a

nozzle adjustment device, in perspective, wherein the nozzle is adjustable not only radially but in all other directions. In Figure 42 is shown, in addition to the associated adjusting equipment, only threaded rod 94 and its adjusting attachments, it being understood that rod 94 connects preferably into the same type of T fitting 95 with its other attachments as shown in Figures 41a, 41b and 41c, although T fitting 95, with its other attachments, is not shown in Figure 42. Threaded rod 94 is slideable in hole 141 drilled in block 144, and positioned by adjusting nuts 97 and 97', and locked in place by lock nut 98. In hole 145 drilled in block 144 at right angles to and set apart from hole 141, slides rod 146, which may be fixed tightly in the desired position in hole 145 by set screw 147. The other end of rod 146 slides in hole 149 of block 148, of the same construction as block 144, having two holes 149 and 150 drilled therein at right angles to and set apart from one another. Rod 146 is fixed tightly in the desired position in hole 149 by set screw 151. In hole 150 slides rod 152, which is fixed tightly in the desired position by set screw 153. The other end of rod 152 is threaded at its extremity and screwed tightly into threaded hole 154 in back plate 60 (of casing 59), a fragmentary portion of plate 60 being shown. As will be apparent, by the adjustment device of Figure 42, nozzle 81 (not shown), but attached as previously described to threaded rod 94, is adjustable in all directions, may be set accurately to the desired position, and may be advanced or retracted radially as desired.

Instead of the union hose couplings 142 and 142' which are shown in conjunction with hose clamps 143 and 143' to connect flexible hose 93 to T 95 as shown in Figures 41a and 41c, there may be used half union and nut fittings, in connection with a tubing capable of being secured by a flared end. A metallic tubing may be used if it may be bent into proper shape without injury, but I prefer to use a flexible or semi-flexible tubing of plastic material such as "Saran" or other plastic for my purpose. By the use of this type of tubing, instead of flexible hose 93 which may suitably be of the fabric reinforced rubber type, I am able to employ a simpler fitting yet one fully as easy of connection as union hose couplings 142 and 142' and hose clamps 143 and 143', shown in Figures 41a and 41c. Figure 43 is a sectional view of such a fitting. In Figure 43, numeral 155 represents a length of tubing such as Saran tubing (in fragmentary form), end 156 of which is flared to fit into nut 157, which may also be of a plastic such as Saran, or of metal if desired. Nut 157 screws on to half union 158 to make a leak proof joint by pressure on flared end 156 of tubing 155, between joint surface 159 of half union 158 and joint surface 160 of nut 157, and to hold flared end 156 firmly in place. The outer end 161 of half union 158 is threaded to fit into the side outlet of T 95 (shown in Figures 41a, 41b and 41c, but not shown here). Half union 158 may also be either of plastic such as Saran, or metal as desired. For the attachment of the other end (not shown) of tubing 155 into conduit 78a (not shown but shown in Figure 41c), a similar fitting consisting of a half union and a nut may be used and connected by an ordinary pipe coupling to pipe nipple 178 (not shown, but shown in Figure 41c), or the half union may if desired be of a female construction at its outer end for screwing on to the male pipe thread of pipe nipple 178, instead of being provided with a male pipe thread as shown for half union 158 at 161.

An example of such a preferred type of nozzle is shown in Figures 44a and 44b. In these figures, 81 is a nozzle, made for example from a steel pipe plug, having a square end 162 adapted for taking a wrench, and male pipe threaded end 163, adapted to be screwed into a corresponding female thread (such for example as in the lower end of T fitting 95 in Figures 41a, 41b and 41c). 164 is a cylindrical channel of appropriate size, drilled 10 in nozzle 81 centered on its longitudinal axis. The liquid or slurry passes through nozzle 81 in the direction indicated by the arrow in Figure 44a, the jet issuing from the orifice end of nozzle 81 opposite the end adjacent the arrow.

15 As specific illustration of such a pipe plug nozzle, I can state that I have found that a nozzle made from a solid steel $\frac{1}{8}$ " pipe plug, that is to say a pipe plug suitable for screwing into a $\frac{1}{8}$ " female pipe thread, is very satisfactory. The length of such plugs is approximately .75", and the length of the cylindrical channel drilled therein is thus also approximately .75" as the channel is drilled on the longitudinal axis of the plug. The diameter of the channel is approximately .070" in one case, and approximately .090" in another. Nozzles with a channel diameter as small as .0277" may be used, as shown in my above referred to application Serial No. 718,649.

30 As stated previously herein, the disclosure of my above referred to copending application Serial No. 449,492 describes the treatment of material, particularly pigment such as calcium carbonate suspended in a liquid, by means of the machine described and claimed herein. Other pigments in liquid suspensions may also be treated. The machine will also find use in treatment not only of suspensions or dispersions of solids in liquids, but also in the treatment of more than one substance, 40 material or liquid fed to it at the same time, in the treatment of one liquid suspended in another such as emulsions, as well as in the treatment of colloidal suspensions and liquids. The liquid used in the above solutions, mixtures, suspensions, 45 emulsions and the like may be water, aqueous liquids, non-aqueous liquids inorganic or organic, examples of the latter being organic solvents, oils or the like; or liquefied gases may be used, or gas in solution in a liquid, if the machine is employed. 50 under pressure or at a sufficiently low temperature, or liquefied solids may be used if the machine is employed at a temperature sufficiently high for the purpose.

55 While I have stated that the rotor element in my machine may be driven by a directly connected motor or steam turbine, any other source of motive power may be employed as the driving means; and if desired, the driving means may be indirectly connected.

60 While my rotor element may be driven at any peripheral speed desired, any peripheral speed of the rotor element lower than 30 feet per second has practically little if any effect and therefore I do not prefer to operate at lower than that peripheral speed. Actually peripheral speeds of 30 feet per second or somewhat higher, while having an appreciable effect, have only a relatively small effect. Since the effect increases as the peripheral speed increases, I therefore prefer to use 70 higher peripheral speeds, for example 300 to 600 feet a second or thereabouts. A 3600 R. P. M. motor (approximately 3520 R. P. M. under load) directly connected to a 36" diameter circular saw gives a peripheral speed of 553 feet per second 75 with a correspondingly lower speed as the circular

21

saw is decreased in diameter by periodic grinding. It generally does not pay to grind the saw much below 24" in diameter, which reduces the peripheral speed to about 369 feet per second, as usually the increased efficiency obtained by replacing the worn saws with new saws is worth more than the cost of the replacement saws.

While, of course, other means for supplying the liquid or slurry under pressure to the nozzles may be employed, a suitable pump is very convenient for the purpose.

My machine may, if desired, be so constructed that the casing in which the rotor element operates may be maintained either under atmospheric, superatmospheric or subatmospheric pressure, that is, in regard to the pressure of the gas such as air, surrounding the rotor element. Superatmospheric pressures surrounding the rotor element would appear to have no decided advantage, except when treating some volatile material or material containing a constituent which it was desired to retain therein, such as a gaseous constituent, which would otherwise be released at atmospheric pressure. Subatmospheric pressure might be of some advantage under some conditions, such as by the reduction or elimination of air resistance to the rotor element and by permitting better striking by the striking surfaces of the rotor element by reducing or eliminating any film of air or other gas between these surfaces and the jets of liquid or slurry.

In regard to the power for driving the rotor element in my machine, I have found in commercial practice when using a 36" diameter circular saw $\frac{1}{4}$ " in thickness at approximately 3520 R. P. M. (under load), treating 40 to 50 gallons per minute of fairly concentrated slurry, that approximately 50 to 70 H. P. is required, that is to say approximately 1 to 1.5 H. P. per gallon of slurry per minute. In practice, for such operation I employ a 75 H. P. motor. Where I wish to treat 85 or 90 gallons per minute I employ a larger motor, usually one of 125 H. P.

I have made a stroboscopic examination of my machine in operation on water employing only one jet, the machine being equipped with a glass door for observational purposes, in order to determine the actual course taken by the liquid or slurry after it has been struck by the rapidly moving saw tooth. The splattered water came out as a kind of sheet tangential to the saw, the forming edge of the sheet which could be seen being slightly forward of the radial plane of the face of the tooth in question which was held apparently motionless by the stroboscope. With one jet, therefore, the saw splattered water in a tangential sheet in all directions slightly forward (in the direction of rotation of the saw) of the radial plane of the tooth. When using a plurality of nozzles, the forward part of the sheet of splattered water from one jet is naturally checked and merges with the forming edge of the sheet of splattered water from the succeeding jet. Thus when employing a plurality of nozzles, particularly nozzles spaced reasonably closely around the periphery of the circular saw, as is my preferred positioning of the nozzles, the thus impeded splatter from the striking of the jets by the saw teeth becomes, in essence, substantially a cylindrical surface of a diameter approximating that of the saw, the cylindrical surface being substantially concentric with the shaft of the saw, and rotating slowly in the direction of rotation of the saw with little force. It is evident that it is highly desirable to provide open space on

22

both sides of the periphery of the rotor element, such as I provide in the two adaptations of my machine shown in Figures 1 to 4, and 6 to 8 respectively, as this permits the immediate freeing of the liquid from the tooth surfaces, keeping them clear for the striking of the next successive jet. It is thus evident that any arrangement whereby pockets or buckets might be formed by the striking surfaces such as teeth or the like of a rotor element by plates or the like, for example located on the end surfaces of a circular saw or other rotor element, the plates being for instance of substantially the same diameter as the rotor element from the outer extremity of one striking surface to the outer extremity of the diametrically opposite striking surface, would have a very bad effect on the efficiency of my machine, as it would result in flooding the pockets or buckets so formed with liquid or slurry, and thus would tend to prevent the entry of the tip ends of the successive jets in front of what should ideally be the substantially liquid free faces of the striking surfaces of the rotor element. It is thus evident that, because of the great loss of efficiency entailed by its use, any such design of a rotor element is not my preferred design, and in fact the use of a rotor element such as a circular saw presents a very great advantage over any such design.

So far in this specification I have described my machine chiefly from the standpoint of the treatment of liquids and slurries therein. It is, however, applicable also for the treatment of material other than in liquid form. I shall now illustrate such use, particularly by reference to two other of my copending applications.

In my copending application, Serial No. 453,469, filed August 3, 1942, now abandoned, to which cross reference is hereby made, the disclosure of which is made a part hereof, and of which the present application is also a continuation in part, I have disclosed a process, and machines for conducting the same wherein material, particularly calcium carbonate, associated with liquid so that it exists in paste form, is, in one adaptation of said process extruded under pressure through a nozzle, e. g. by means of a screw conveyor device, in the form of a cylinder, ribbon, sheet or the like, in close proximity to the periphery of a rapidly rotating element, such as a circular saw, whereby the paste is struck by the teeth of the circular saw. Thus it is apparent that said process may be carried out in my machine by providing therein a nozzle or nozzles, adapted for the extrusion therefrom under pressure of materials in paste condition as a jet or jets, in the form of a cylinder, ribbon, sheet or the like, into the path of the rotor element. The machine is described, but not claimed, in my copending application Serial No. 453,469. The machine is claimed herein.

A simple nozzle with feed device broadly described in my said copending application, is shown herein in one form in Figure 45 for purposes of illustration. In Figure 45, 203 is the cylindrical body of a feed device for feeding material in paste form to one or more nozzles. Cylindrical body 203 is fed by hopper 204, into which paste is supplied. The paste is transferred from hopper 204 through cylindrical body 203 by means of screw conveyor 205 preferably of heavy construction, fitting cylindrical body 203 fairly snugly, mounted on shaft 206, and driven by any suitable means such as gear 207. The direction of rotation of screw conveyor 205 is such that the paste is advanced in the direction of the arrow adjacent to cylindrical body 203. The paste is then extruded through

nozzle 208, in the direction of the adjacent arrow, as a jet (not shown) intended to be a continuous cylinder, but which may also be a continuous ribbon, sheet or the like of the paste. The cross sectional area of cylindrical body 203 is preferably much larger than the cross sectional area of the channel of nozzle 208, and thus the rotation of screw conveyor 205 builds up a pressure at the inlet of nozzle 208 resulting in the extrusion of paste therefrom under pressure. This pressure 10 may be regulated by the speed at which screw conveyor 205 is driven. The jet of paste is extruded into the path of, and is struck by, striking surface 73 of rotor element 72 (shown in fragmentary form) traveling in a direction directly forward (toward the observer). While Figure 45 shows my preferred construction and positioning of such a nozzle and feed device, of course, if desired, the longitudinal axis of cylindrical body 203 may be arranged in a plane of rotation of 15 rotor element 72, instead of at right angles thereto as illustrated, or in any other desired position, and the jet of paste may be extruded in the various directions in respect to rotor element 72 as already described herein for jets of liquid. Manifestly, also, the jet of paste may be merely one of a plurality of such jets arranged adjacent to the periphery of rotor element 72; and either a single nozzle of the type illustrated, or a plurality if used, may be adjustable in respect to the periphery of rotor element 72, to provide for change in diameter thereof, if the rotor element employed be of such a type. The struck 20 paste is removed by suitable means.

In my copending application, Serial No. 455,-367, filed August 19, 1942, now abandoned, to which cross reference is hereby made, the disclosure of which is made a part hereof, and of which the present application is a continuation in part, I have disclosed a process, and machines for conducting the same, wherein material, particularly calcium carbonate, either in dry form, or associated with sufficient liquid so that it exists in slightly moist form (but with insufficient liquid to form a paste), is, in two of its adaptations, either extruded under pressure through a nozzle in shaped condition as a kind of a solid jet or jets in the form of a continuous cylinder, ribbon, sheet or the like, in close proximity to the periphery of a rapidly rotating element, such as a circular saw, or is blown in finely divided form by means of air, steam or other gas through a nozzle, likewise in close proximity to the periphery of a rapidly rotating element, such as a circular saw, whereby the jet of extruded material, or the jet consisting of the stream of gas containing finely divided material, respectively, is struck by the teeth of the circular saw. Thus it is apparent that either adaptation of 45 said process may be carried out in my machine by providing therein a nozzle or nozzles adapted for the extrusion therefrom under pressure of material in dry or somewhat moist condition as a kind of solid jet or jets into the path of a rotor element, or by providing a nozzle or nozzles adapted for conveying finely divided solid material in a stream of gas as a jet or jets into the path of a rotor element. The machine is described, but not claimed, in my copending application Serial No. 455,367. The machine is 50 claimed herein. A nozzle and feed device similar in general to that shown in Figure 45 is suitable for the extrusion of material in dry or somewhat moist condition as a kind of a jet or jets. This has already been broadly described 55

in my said copending application. A nozzle and feed device suitable for conveying finely divided solids with a gas under pressure, such as air, steam or the like, is also broadly described in said copending application, and one form of this is shown herein in Figure 46 for purposes of illustration. In Figure 46, 209 is a pipe (shown in fragmentary form) for conveying gas, such as air or steam, under pressure in the direction of the arrow adjacent thereto. Hopper 210 (shown in fragmentary form), containing the material to be treated in finely divided form (under pressure if desired), is connected into the side of pipe 209 diagonally in the direction of the gas stream in pipe 209. The stream of gas passing the junction of hopper 210 and pipe 209 blows the finely divided material from hopper 210 with it through nozzle 211, from which issues, in the direction of the adjacent arrow, a jet (not shown) consisting of gas and finely divided material, into the path of, and is struck by, striking surface 73 of rotor element 72 (shown in fragmentary form) traveling in a direction directly forward (toward the observer). While Figure 20 46 shows my preferred construction and position of such a nozzle and feed device, of course, if desired, the nozzle and feed device may be arranged in any other desired position, and the jet may issue in the various directions in respect to rotor element 72 as already described herein for jets of liquids. Manifestly, also, the jet may be merely one of a plurality of jets arranged adjacent to the periphery of rotor element 72; and either a single nozzle of the type 25 illustrated, or a plurality if used, may be adjustable in respect to the periphery of rotor element 72, to provide for change in diameter thereof, if the rotor element employed be of such type.

Where I use the word "liquids," I mean it to 30 include not only readily flowable liquids or suspensions or the like, but also, thick and viscous liquids or suspensions or the like, up to the point where they may approach the plastic or even 35 pasty condition.

When a jet, or its longitudinal axis, is stated 40 herein or in the claims, to lie in a plane of rotation, or be located in a plane of rotation of a rotor element, such for example as a circular saw, it is intended to mean that a plane of rotation of said rotor element passes through said jet substantially parallel to the longitudinal axis of 45 said jet.

By the word "element" I mean the whole unit 50 employed and not merely a part thereof; and by the word "member," e. g. as of an "element," I mean a part thereof, either integral or connected therewith.

As indicated above, the apparatus has important uses in various fields, and it is particularly 55 valuable in the treatment of such material as artificially prepared calcium carbonates used, for example, in coated paper or in water paints. The use of the present apparatus reduces the oil absorption of artificially prepared calcium carbonate used in paints, enamels, etc., and greatly reduces the adhesive requirements of such material used, for example, in coated paper or in water paints.

Where in the claims I speak of "high peripheral speed," I mean a peripheral speed of not less than 30 feet per second, and preferably much higher, such for example as the peripheral speeds higher than 30 feet per second previously cited herein.

Cross reference is hereby made to my copend-

ing application Serial Number 346,661, filed July 20, 1940, now Patent No. 2,385,379, dated September 25, 1945.

While I have described in detail the preferred embodiments of my invention, it will be understood that these are presented for purposes of illustration only, are not limiting, and may be widely varied without departing from the spirit of my invention or the scope of the subjoined claims.

I claim:

1. Apparatus for treating a liquid slurry of material by impact shock, comprising a disc rotatable in one direction, means for rotating said disc at a high peripheral speed in said direction, said disc being provided with peripheral teeth each having a leading face lying substantially in a plane containing the axis of rotation of said disc and a following face sloping inwardly away from said direction of rotation, a plurality of circumferentially spaced nozzles substantially surrounding the periphery of said disc and substantially equidistantly spaced from said teeth, means for supplying the slurry material to said nozzles under pressure, said nozzles being positioned in the plane of rotation of said disc and being so oriented as to provide substantially radial jets which are struck by said leading faces when said disc is rotating, the width of said teeth and the thickness of said disc adjacent thereto being at least equal to and only slightly greater than the width of said jets whereby substantially all of the slurry material from said jets will be struck by said leading faces and will immediately be discharged therefrom, and a casing enclosing said disc and said nozzles, said casing having walls all of which are spaced from said teeth sufficiently to prevent substantial recontact of the slurry material with said teeth.

2. Apparatus for treating a liquid slurry of material by impact shock, comprising a disc rotatable in one direction, means for rotating said disc at a high peripheral speed in said direction, said disc being provided entirely therearound with closely arranged peripheral teeth each having a leading face lying substantially in a plane containing the axis of rotation of said disc, a plurality of circumferentially spaced nozzles adjacent the periphery of said disc and substantially equidistantly spaced from said teeth, means for supplying the slurry material to said nozzles under pressure, said nozzles being positioned in the plane of rotation of said disc and being so oriented as to provide substantially radial jets which are struck by said leading faces when said disc is rotating, the width of said teeth and the thickness of said disc adjacent thereto being at least equal to and only slightly greater than the width of said jets whereby substantially all of the slurry material from said jets will be struck by said leading faces and will immediately be discharged therefrom, and a casing enclosing said disc and said nozzles, said casing having walls all of which are spaced from

said teeth sufficiently to prevent substantial recontact of the slurry material with said teeth.

3. Apparatus adapted for treating a liquid slurry of a material such as a pigment by impact shock, comprising a circular saw rotatable in one direction, means for rotating said saw at a peripheral speed in said direction not lower than substantially 30 feet per second and not higher than substantially 600 feet per second, said saw being provided with peripheral teeth each having a leading face lying substantially in a plane containing the axis of rotation of said saw, and a following face sloping inwardly away from said direction of rotation, at least one nozzle positioned adjacent the periphery of said saw, means for supplying the slurry material to said saw under pressure to deliver a jet having a speed not lower than substantially 23 feet per second and not higher than substantially 556 feet per second, said nozzle being so positioned in the plane of rotation of said saw and being so oriented as to provide a substantially radial jet which is struck by said leading faces when said saw is rotating, the width of said teeth being at least equal to, and not greater than approximately 4 times, the width of said jet whereby substantially all of the slurry material from said jet will be struck by said leading faces and will immediately be discharged therefrom, and a casing enclosing said saw and said nozzle, said casing having walls all of which are spaced from said teeth sufficiently to prevent substantial recontact of the slurry material with said teeth.
